UNITED STATES PATENT OFFICE.

PETER DODD AND JAMES HENRY THOMAS, OF NEWARK, NEW JERSEY; SAID THOMAS ASSIGNOR TO JOSEPHINE THOMAS, OF SAME PLACE.

AUTOMATIC HORSE-FEEDER.

SPECIFICATION forming part of Letters Patent No. 378,909, dated March 6, 1888.

Application filed September 24, 1887. Serial No. 250,591. (No model.)

To all whom it may concern:

Be it known that we, PETER DODD and JAMES HENRY THOMAS, citizens of the United States, residing at Newark, in the county of 5 Essex and State of New Jersey, have invented a new and useful Improvement in Automatic Horse-Feeders, of which the following is a specification.

Our invention relates to an improvement in 10 automatic horse-feeders; and it consists in the novel construction and combination of parts, which will be more fully hereinafter set forth, and particularly pointed out in the claims.

The primary object of our invention is to 15 provide a releasing-lever, in connection with the alarm mechanism of a clock, whereby the hinged bottom of a feed box or chute may be released and allowed to swing downward to permit the grain to pass out into the feed- 20 trough of the animal.

The secondary object of our invention is to 25 provide an automatic feeding device for horses and other animals, the parts of which are simple and effective in their construction and operation, strong and durable, and positive and reliable in their action and ultimate result.

We attain these objects by the device illustrated in the accompanying drawings, wherein like letters of reference indicate similar parts 30 in the several views, and in which—

Figure 1 is a perspective view of our improved device, showing a feed-box with hinged bottom door open in dotted lines, a supporting casting or bracket, and a portion of the operating-lever. Fig. 2 is a similar view looking from the rear side. Fig. 3 is a detail view of the casting B. Fig. 4 is a detail sectional view showing the recess in the hinged door.

A indicates a feed box or chute, which is 40 secured in a proper position relatively to the feed-trough of the animal, and is provided with a bottom hinged door, A', which is formed with a small recess, a, in its unhinged edge for the reception of the lower end of the lever.

B indicates a curved-shell casting having an 45 arm, b, which is secured to the side of the feed-box, and with a rear annular ring, b', and recesses b² in its front edge. This casting is adapted to support an ordinary alarm-clock, 50 C, the feet c of which enter the recesses b², and

the back thereof rests against the annular ring b'. The winding and setting attachments on the rear of the clock are readily accessible through the said ring b'; but for more convenient winding and setting of the clock a 55 rod, c', is secured to the top of the clock for removing the same, having a ring, c², attached to the top thereof. This rod c' is virtually the alarm-bell standard, which bell is removed in this instance, so as to avoid frightening the 60 animals. The alarm-striker c³ is allowed to play backward and forward without striking anything, and the only noise produced is the slight whirring sound caused by the uncoiling action of the spring actuating the alarm. 65

The shaft or spindle S, upon which the alarm-spring is mounted, is extended from the rear side of the clock, and is provided with a cog-wheel or pinion, S', and immediately outside of the pinion S', and integrally formed 70 with the shaft S, is a winding thumb-piece or handle, s.

In the rear of the casting B, and at the lower portion of the feed-box A, a fulcrum-plate, D', is secured, which is provided with a fulcrum 75 extension or arm, d'. The fulcrum-ear d, integrally formed with the lower part of a lever, D, is secured to the fulcrum-extension d' by a bolt, D², passing through said parts, and which forms a pivotal connection between the same. 80 The lower end of the lever D is constructed or bent into the form of a hook, d², which is adapted to engage with the recess a in the door A' to hold the same closed when the alarm mechanism is set. The upper end of the said 85 lever D is provided with an arm, D³, which is formed with a curved rack, d³, on its upper edge.

The clock-alarm mechanism having been set for a certain hour, it is placed in the bracket 90 B in such a manner that the pinion S' will engage with the rack d³ on the upper edge of the arm D³ at the upper part of the lever D, it being understood that the lower curved end of the said lever D has been adjusted in engagement with the under side of the door A'. The feed is then placed in the box A, the bottom door, A', being held closed against the weight thereon by the lower end of the lever. When the feeding-hour, as indicated by the alarm- 95 100

dial, arrives, the alarm mechanism is set in motion as in the ordinary alarm-clock, the pinion S' revolves, and the lever D, through the rack-arm D³, is moved in the direction of the arrow, so that the lower end thereof is disengaged from the edge of the door A', which will drop and allow the contents of the feed-box to run into the feeding-trough.

The front recesses for the feet of the clock 10 in the front lower edge of the bracket B are so formed that when the clock is shoved back therein the cog-wheel or pinion S' will mesh with the rack d³ on the arm D³. By extending an arm from the lever, running across to 15 other boxes contiguous with and attached to other levers, and with the assistance of spiral springs attached to box and top of the lever, one clock will open several bottoms.

The advantages and conveniences of our device are many and varied. The mechanism 20 may be set to feed at any time desired during the day or night.

Marketmen, truckmen, and others are often 25 delayed in the early morning by waiting until their animals have finished feeding. By using our automatic feeding device the animals are fed at a set hour before they are required for use, and delay thereby prevented. If the animal comes into the stable in a too warm condition to be fed, a little hay may be thrown 30 into the rack and the feed in connection with our automatic device administered later, when his condition will permit him to receive the same without harmful consequences.

35 Aside from the above advantages, animals may be fed during the day without the attention of any one, with healthful regularity, thereby saving the time and attention of farm-hands and others.

40 Many minor changes in the construction and arrangement of the parts of our device might be made and substituted for those shown and described without departing from the nature and principle of our invention.

45 Having thus described our invention, what we claim as new is—

1. An automatic feeding device comprising

a feed-box with a lower hinged door, a lever having a rack-arm, and an alarm-clock having a pinion in connection with the alarm mechanism adapted to engage with the rack-arm of the lever, substantially as described.

2. The automatically - operating feed - box, comprising the box proper having the lower hinged door, the lever having the lower curved 55 end and the rack-arm at the upper end thereof, the bracket-casting constructed as set forth, and the clock supported in said casting and having an alarm mechanism, with one portion of which a pinion is provided which engages 60 with the rack-arm of the lever, substantially as described.

3. The combination, with the side of the feed-box, of the curved-shell bracket-casting having the front recesses and the rear annular 65 ring adapted to support an alarm-clock, as set forth, and the lever D, fulcrumed to said box, substantially as described.

4. The combination of the extended shaft S, 70 of the clock-alarm mechanism having the pinion S' thereon, and the integral thumb-piece, and the lever D, carrying a rack-arm on its upper end to engage with the pinion S', and having its lower end curved, as set forth, whereby a door is held in a closed position 75 and released when desired, substantially as described.

5. An automatic feed-box comprising the box proper having a hinged door at its lower end provided with a recess, a, the bracket-casting 80 B, the alarm-clock C, having the extended shaft S and pinion S', and the lever D, having the lower curved end and provided with the upper rack-arm fulcrumed on the plate D', substantially as described.

In testimony that we claim the foregoing as our own we have hereto affixed our signatures in presence of two witnesses.

PETER DODD.
JAMES HENRY THOMAS.
